INGOT MOLD CAR

Harry A. Davis, New Brighton, and August F. Kroen, Beaver Falls, Pa., assignors to Treadwell Construction Company, Midland, Pa., a corporation of Pennsylvania

Application September 2, 1944, Serial No. 552,510

4 Claims. (Cl. 105—165)

1

This invention relates to railroad cars and particularly to railroad cars of the type commonly used in and around steel plants for the transportation of ingots, ingot molds, or other very heavy metallic bodies.

When ingots, ingot molds, heavy machines, and the like are to be transported, the problem of the heavily concentrated load is met with and the rolling stock provided for the transportation of such objects must be designed with this in mind. Freight cars of the type customarily used in the transportation of ingots are relatively short, fabricated entirely of metal, and have flat decks without upwardly extending side walls. The running gear comprises axles of heavy type, large bearings and, generally, heavy helical compression springs. It is frequently necessary to push or pull laden cars of this type around curves of short radius and car designers have heretofore met with substantial difficulty in designing cars for the transportation of ingots or the like which have not only the ability to support great concentrated loads, and to stand up under the shocks of shifting and moving along trackways, but which likewise can be moved with facility around such short radius curves.

One object of the present invention is to provide a railroad car of the general type indicated which may be moved around short radius curves with ease, the car being supported upon spaced two-wheeled axles which are individually rotatable about vertical axes, the conventional four-wheeled trucks being dispensed with. The well known four-wheeled truck, while of great general serviceability and therefore widely used, embodies axles which remain parallel under all circumstances being mounted respectively, in bearings which are held against relative movement in a horizontal plane. This lack of flexibility is a decided disadvantage when the truck is negotiating curves, resulting in some sliding of the wheels on the tracks in almost every instance and where the curves are sharp, in frequent derailments. A truck constructed in accordance with the present invention, and including spaced axles relatively rotatable about parallel vertical axes has, on the other hand, the capacity to negotiate sharp curves with negligible wheel sliding and practically no tendency to leave the rails along which it is moving. The practical utility of such a truck, and its value where many curves are to be negotiated, as around steel plants, is very great.

A further object of the invention is to provide a car of the type suggested which includes two bolsters which have rolling contact with each

2

other at approximately the center of the car so that any shock which might happen to be imposed upon one bolster is communicated to the second bolster directly instead of being communicated to such bolster through the car body. As a result of this arrangement the king-pins which are customarily employed to connect the car body and bolsters are not subjected to shearing strains in the manner heretofore experienced.

10 A further feature of importance which is included in the novel and improved railroad car consists in the provision of bolsters which not only make rolling contact with each other through all of the angles through which they may be rotated when the car is in use, but which likewise make contact, or substantially make contact, at all times with a coupler block or head through which the strains imparted to the car by the coupler are transmitted to the car body. With 15 this arrangement the shocks incident to shifting or sudden starting or stopping of the train, and it will be understood that cars of the type contemplated are not provided with brakes, may for the most part be transmitted from coupler block to 20 coupler block through the bolsters instead of through the car body and king-pins. The arrangement is such, therefore, that the strains imposed upon the king-pins or any other means connecting the bolster to the car body are minimized 25 and a car of increased ruggedness is provided.

30 In the accompanying drawings one form of railroad car embodying the invention is illustrated. It will be appreciated by one skilled in the art that the design and arrangement of the 35 component elements of the invention may be considerably modified in adapting it to cars of various sizes and intended for use in the performance of various special functions. That form of the invention which is illustrated, therefore, is set forth 40 by way of example only.

In the drawings:

Figure 1 is a plan view of a car body embodying the invention, portion of the deck of the car being broken away, and likewise portion of one 45 bolster, in order that portions of the running gear may be more clearly perceived.

Figure 2 is a section on line 2—2 of Figure 1, on a somewhat larger scale;

Figure 3 is a section on line 3—3 of Figure 2;

Figure 4 is a section on line 4—4 of Figure 2;

Figure 5 is a section on line 5—5 of Figure 2; and

Figure 6 is a section on line 6—6 of Figure 5.

As clearly to be seen in Figure 1 the car selected 55 for illustration by way of example is rectangular

in plan and relatively short. The deck of the car is indicated at 10 and preferably comprises metallic plates of substantial thickness, well adapted to withstand without buckling the heavy concentrated loads placed upon it and to withstand the heat of any ingots or ingot molds which are to be carried. The car frame upon which the deck 10 is supported may vary widely in its details of construction, the invention being nowise limited in this respect. At the ends of the frame, however, are located the coupler blocks 11 and 12, these coupler blocks being preferably welded to the frame members so as to comprise rigid portions of the frame.

By means of a coupler or link, not illustrated, each coupler block may be connected to the similar coupler block of an adjacent car so that a train of such cars of any desired length may be formed. The frame includes, at each end, a relatively heavy transversely extending block 13, directly underlying the deck 10 and the ends of which are received between the upper and lower flanges of the side sill members 14. Projecting downwardly from the undersurface of this block 13 is a short cylindrical extension 13', this portion of the block projecting into a shallow cylindrical recess formed in the upper surface of the underlying bolster 15, the bolster being thus restrained against movement in a horizontal plane relatively to the car frame block 13 directly above it, but being free to rotate horizontally about the vertical axis of the cylindrical extension 13' of the car frame block. A king-pin of conventional type is indicated at 16, the axis of the king-pin being coincident with the axis of the cylindrical projection 13' of the block 13 and the king-pin passing through and closely fitting within a cylindrical aperture formed in the bolster 15.

As viewed from above the bolster 15 is generally rectangular but is cut away at its ends to receive the bearing blocks 17 within which are housed the roller bearings 18 which encircle the ends of the axle 19, and likewise cut away to receive the upper portions of the wheels 20 fixed on axle 19. By thus cutting away the bolster, and permitting the upper portions of the several wheels to occupy positions between the planes of the horizontal upper and lower surfaces of the bolster, a very substantial reduction in the overall height of the car is realized. It is of course desirable to minimize as much as possible the heights of cars of this type, thus keeping their centers of gravity low. The present design, with cut away areas, wells or pockets formed in the bolster ends permits this type of car to be made with center of gravity very low and with the overall height desired without sacrificing strength. Even with wheel pockets of substantial size formed therein each bolster 15 is amply strong and well able to accomplish its intended functions.

It will be observed that horizontal extensions 17' of the bearing block 17 constitute abutments for the lower ends of the heavy helical compression springs 21 and that upwardly extending flanges integral with the spring abutment 17' comprise lateral guides or confining walls for these springs. Underlying the bearing block 17 and horizontal spring abutment 17' is the lower horizontal midportion of a carrier 24 the vertical end portions 24' of which are provided with spaced ears 24² at their upper ends, each pair of spaced ears 24² being provided with aligned apertures which register with an aperture formed

in ear 13² of the bolster, a retaining pin 25 projecting through these registering apertures, as shown clearly in Figure 1. Each member 24 is thus connected at its upper ends to the bolster and constitutes a limiting stop and guide for the bearing block 17 and the integral spring abutments 17'. The carrier members 24 also serve to positively secure the bearing blocks, springs and axles to the car body, though permitting all necessary flexing of the springs at all times, so that these elements will move with the car when the car is lifted from the track, as by means of crane operated cables or chains attached to the car body. The bearing block is formed with the customary vertical grooves or slots 17² to receive the downwardly projecting guides 26 formed integrally with the bolster, the relative movements of the bolster and axle and block being thus closely restrained so as to be vertical only.

Each bolster 15 has two diametrically opposed outwardly facing cylindrical surfaces, the outer of such surfaces being indicated at S and the inner at S'. Both such surfaces are centered on the axis of the king-pin 16 previously referred to. The surface S is immediately in rear of the surface 53 of the coupler head 11, or at least in rear of that portion of the coupler head 11 which lies in the plane of the bolster. The inner surface S' of the bolster is adapted to have rolling contact with a similar surface of the adjacent bolster, or to be at all times in the immediate proximity of such surface of the adjacent bolster, the surfaces S' of the two adjacent bolsters comprising the outer surfaces of curved transversely extending plates 23, the upper and lower edges of which are welded to the curved peripheries of the parallel horizontal plates 29 and 30, respectively, these last mentioned plates being welded to the previously described portion of the bolster 15 and in reality forming integral portions thereof.

The arrangement is such that, as the bolsters swing about the vertical axes of the king-pins 16 as the car rounds a curve, the mutually facing surfaces of the curved members 23 of the bolster either roll upon each other or at all times are in very close proximity to each other. It is desirable to limit the possible swinging movement of each bolster about its king-pin and to that end stops are mounted upon the bolster extensions just described, two stops upon each such bolster extension, these stops being indicated at 32 in the drawings. They are so positioned with relation to each other, and are so dimensioned, that contact of mutually facing stops will occur when the bolsters of the car have rotated through the maximum angles considered to be desirable. The stops may be, and preferably are, detachably secured in position so that stops of different sizes may be employed to limit the angle of swing of each bolster about its king-pin to that angle through which the bolster must rotate when the car is moving around the curve of smallest radius along the trackway upon which the car moves.

Having thus described the invention what is claimed as new and desired to be secured by Letters Patent is:

1. In a railroad car of the type described, in combination, a car body, coupler blocks mounted on the ends of the car body, bolsters beneath and supporting the car body, said bolsters being mounted for rotation about parallel axes and each bolster having two surfaces curved about its axis of rotation one such surface being immediately adjacent one of the coupler blocks and the

other immediately adjacent the correspondingly curved surface of the second bolster.

2. In a railroad car of the type described, in combination, a car body, coupler blocks mounted on the ends of the car body, two bolsters beneath the car body, each bolster being rotatable about a vertical axis and, in each of its possible angular positions, extending from the immediate proximity of the adjacent coupler block to the immediate proximity of the other bolster.

3. In a railroad car of the type described, a car body, coupler blocks mounted on the ends of the car body, and means independent of the car body for communicating shock imposed upon one coupler block to the other coupler block, said means comprising two bolsters interposed between said blocks and each rotatable about a vertical axis, said bolsters together constituting a continuous means, for all angular positions of said bolsters, for transmitting forces due to impact upon one 20 coupler block to the other coupler block.

4. The combination set forth in claim 3 in which each bolster is provided with two surfaces curved about its axis of rotation, one such sur-

face being always in close proximity to the coupler block and the other curved surface being always in close proximity to the surface of the second bolster.
